KNITTING MACHINE FOR KNITTING PLAIN AND PURLED STITCHES

Erich Piltz, Markdorf, Baden, Germany, assignor to
Willy Werner Lenkeit, Markdorf, Baden, Germany

Application February 10, 1954, Serial No. 409,463

Claims priority, application Germany May 13, 1953

8 Claims. (Cl. 66—6)

This invention relates to hand-operated knitting machines and it has particular relation to machines of this type in which different types of stitches, i. e. plain and purled stitches can be alternately knitted.

Manually operated knitting machines comprising a horizontal needle bed, in which the knitting needles lie side by side, an eccentric lock which is movable perpendicularly to the longitudinal direction of the needles and is provided with a thread guide and a stitch stripper or repusher and a looping comb, the upwardly directed teeth of which are arranged between the knitting needles, have been known in the art. However, in these known knitting machines only plain knitted products consisting of plain stitches could be produced, but knitted products, in which plain and purled stitches are alternately knitted, e. g. the border of pullovers, or other knitted products of this type, could not be produced in said known machines.

The main object of the present invention is to eliminate this limitation by a modified and improved knitting machine of simple construction.

According to the invention, the hand-operated knitting machine of the above mentioned type, comprises an additional comb, which is arranged in front of the looping comb and has substantially vertically extending needles, the heads of which are designed in such manner that they are capable of retaining the thread on the needle shafts, whereby the needles of the auxiliary comb are arranged between the horizontal knitting needles, on the insertion of the thread by the thread guide or carrier, for forming spaced stitches of a stitch row.

The needles of the additional or auxiliary comb are designed as machine knitting needles, whereby the auxiliary comb must be arranged movably in approximately vertical direction. In using this arrangement, the whole knitting procedure is mechanized.

It is preferred to fasten the additional comb to swinging arms which are rotatably arranged on the front sides of the underframe or substructure, and the upward and downward swinging motion of which is preferably limited by stop members. A stop means, which can be arranged on the swinging arms, is preferably provided for holding the additional comb in a middle position.

A knock over bar, which is vertically movable on the additional comb, and serves for forming stitches and simultaneously for knocking over the stitches on and from the needles of the additional comb, is connected by releasable fastening means, e. g. screws, to the additional comb. Upon releasing these fastening means, said knock over bar can be vertically displaced in vertical slots provided in the additional comb, or in the knock over bar proper.

If the needles of the additional comb are designed with a cap-shaped head, in view of the knocking over of the stitches by hand, the use of a knock over bar is not necessary.

The needles of the additional comb can be made removable. This has the advantage that, by removing a suitable number of said needles, knitted products can be

2

obtained in which in each row of stitches one purled stitch alternates with two or more plain stitches.

In the appended drawings an embodiment of the invention, to which the invention is not limited, is illustrated 5 by way of example.

Figure 1 is a front view of the complete device according to the invention; Figure 2 is a top view of the device; Figure 3 is a cross-section along line III—III in Figure 2.

Referring now to the drawings in detail, reference numeral 1 denotes the needle bed and 1a denotes the underframe or substructure of needle bed 1. The knitting needles of the machine are denoted 2 and the eccentric lock, which is provided with thread guide or thread carrier 4 and stitch stripper or repusher 5, is denoted 3. The 15 looping comb is shown at 6, the supplementary comb at 7 and needles of the supplementary comb are shown at 8. The needle latches of needles 8 are denoted 8a, and swinging arms for holding comb 7 are shown at 9. 10 and 10a are stop elements for the swinging movement, 11 is a detent for stopping comb 7. Reference symbol 12 denotes a vertically movable knock off bar, while 13 denotes vertical slots with screws in knock off bar 12 and comb 7, respectively, for guiding member 12.

In operating the knitting machine according to the invention, first every second stitch hanging on the knitting needles 2, of the knitted product is drawn over the corresponding auxiliary needle 8 of supplementary or auxiliary comb 7, which is held by member 11 in its middle position, so that now the stitches of the knitted product 20 alternately hang on a needle 2 of the normal needle bed 1 and a needle 8 of auxiliary comb 7. Subsequently, 25 comb 7 is caused by swinging arms 9, which are fastened on the sides of underframe 1a, to swing to its highest position up to stop member 10, whereby the stitches hanging on needles 8 of comb 7, glide under the action of the tension weights behind latches 8a.

Auxiliary comb 7 is now returned to its middle position. Upon actuation of eccentric lock 3, which is provided with a thread guide or carrier 4 and a stitch stripper 40 or repusher 5, on needle bed 1, the new thread is inserted in or applied to the open hooks of needles 2 of needle bed 1, as well as to the open latches 8a of needles 8 of auxiliary comb 7. During the subsequent displacement of comb 7 to its lowest position by swinging arms 9 down to stop member 10a, the old stitch hanging on needles 8, closes latch 8a and catches the inserted thread in the closed hook. Hereupon, knock over bar 12, which is fastened to comb 7 by means of screws in vertical slots of 35 13 of knock over bar 12 and comb 7, respectively, is moved upward, whereby, with the formation of new purled stitches, simultaneously their knocking over is brought about. However, as on needles 2 located between needles 8 of comb 7, formation of plain stitches has taken place, a row of stitches is thus obtained which 45 is formed by alternating plain stitches and purled stitches.

The device embodying the present invention can be easily operated even by inexperienced persons. Moreover, by this device, which contains only one needle bed, a knitted product can be made, which in devices known 50 from the art required the use of two needle beds in hand-operated machines.

It will be understood that this invention is not limited to the specific elements, designs, constructions and other details specifically described above and illustrated in the 55 drawings and can be carried out with various modifications without departing from the scope of the invention as defined in the appended claims.

What is claimed is:

1. Hand-operated knitting machine for alternate knitting of plain and purled stitches comprising a horizontal needle bed, in which the knitting needles lie side by side, an eccentric lock movable perpendicularly to the longitu-

dinal direction of the knitting needles, said lock being provided with a thread guide or carrier and a stitch stripper or repusher, a looping comb, the upward directed teeth of which are arranged between said knitting needles and an additional comb provided with machine knitting needles arranged in front of said looping comb, the needles of the additional comb being located, on the insertion of the thread by the thread guide, for forming spaced stitches of a stitch row, between the horizontal machine knitting needles.

2. A knitting machine as claimed in claim 1, in which the additional comb is movable in approximately vertical direction.

3. A knitting machine as claimed in claim 1, comprising an underframe carrying on its sides swinging arms, to which the additional comb is fastened.

4. A knitting machine as claimed in claim 1, comprising an underframe carrying on its sides swinging arms, to which the additional comb is fastened, and stop means are provided for limiting the swinging movement of the 20 swinging arms.

5. A knitting machine as claimed in claim 1, comprising an underframe carrying on its sides swinging arms, to which the additional comb is fastened, stop means are

provided for limiting the swinging movement of the swinging arms and a detent member is provided for holding the additional comb in a middle position.

6. A knitting machine as claimed in claim 1, comprising a vertically movable knock over bar for knocking over 5 stitches from the needles of the additional comb.

7. A knitting machine as claimed in claim 1, comprising an underframe carrying on its sides swinging arms, to which the additional comb is fastened, stop 10 means are provided for limiting the swinging movement of the swinging arms, a detent member is provided for holding the additional comb in a middle position and a vertically movable knock over bar for knocking over stitches from the needles of the additional comb.

8. A knitting machine as claimed in claim 1, in which 15 the needles of the additional comb are removable.
